[57] **CLAIM**

The ornamental design for golf club head, as shown and described.

DESCRIPTION

FIG. 1 is a right side elevational view of a golf club head showing my new design;
FIG. 2 is an inverted left side elevational view of FIG. 1;
FIG. 3 is a top plan view of FIG. 1;
FIG. 4 is a rear elevational view of FIG. 1;
FIG. 5 is a front elevational view of FIG. 1;
FIG. 6 is a bottom plan view of FIG. 1;
FIG. 7 is a right side elevational view of a second embodiment of a golf club head as disclosed in FIG. 1;
FIG. 8 is an inverted left side elevational view of FIG. 7;
FIG. 9 is a top plan view of FIG. 7;
FIG. 10 is a rear elevational view of FIG. 7;
FIG. 11 is a front elevational view of FIG. 7;
FIG. 12 is a bottom plan view of FIG. 7;
FIG. 13 is a right side elevational view of a third embodiment of a golf club head as disclosed in FIG. 1;
FIG. 14 is an inverted left side elevational view of FIG. 13;
FIG. 15 is a top plan view of FIG. 13;
FIG. 16 is a rear elevational view of FIG. 13;
FIG. 17 is a front elevational view of FIG. 13; and,
FIG. 18 is a bottom plan view of FIG. 13.

The broken line showing of the degree of loft and the number of the club head is for illustrative purposes only and forms no part of the claimed design.
